(57) CLAIM

The ornamental design for a pharmaceutical tablet as shown and described.

DESCRIPTION

This application is cross-referenced to commonly owned and related U.S. design application Ser. No. 29/912,339.

FIG. 1 is a top perspective view of a pharmaceutical tablet in accordance with the present design;

FIG. 2 is another top perspective view thereof;

FIG. 3 is a top view thereof;

FIG. 4 is a bottom view thereof;

FIG. 5 is a front side view thereof, with the tablet horizontally oriented;

FIG. 6 is a back side view thereof, with the tablet horizontally oriented;

FIG. 7 is a left side view thereof, with the tablet vertically oriented; and,

FIG. 8 is a right side view thereof, with the tablet vertically oriented.

The drawings depict a pharmaceutical tablet with four equally sized and shaped sections.

1 Claim, 6 Drawing Sheets
